DOOR OPERATING DEVICE

Wilfred A. Beauchamp, Chicago, Ill., assignor, by
mesne assignments, to The Youngstown Steel
Door Company, Cleveland, Ohio, a corporation
of Ohio

Application November 3, 1932, Serial No. 640,956

4 Claims. (Cl. 268—44)

This invention relates to improvements in door operating devices.

An object of this invention is to provide a door operating device comprising an arm and an actuating lever arranged to move said door toward open and closed positions.

Another object is to provide a door operating device comprising an actuating lever constructed and arranged to serve as the hasp of a locking mechanism for the door and requiring no modification of the remainder of said mechanism.

A further object is to provide a door operating device comprising an arm pivotally secured to a relatively stationary member and an actuating member pivotally supported on said door, the arm and the lever being constructed and arranged to impart both opening and closing movements to the door.

Other objects of the invention will become clear from the following description and the drawings illustrating a preferred embodiment of the invention.

In said drawings:

Figure 1 is a partial elevation of a double door construction showing the application of the door operating device.

Figure 2 is a partial elevation showing the engaged relationship of the parts of the operating device with the door forced toward open position and in dot and dash lines the inoperative position of said parts.

Figure 3 is a horizontal section taken on line 3—3 of Figure 1.

Figure 4 is a horizontal section taken on line 4—4 of Figure 1.

Figure 5 is a plan detail of the closing and opening arm.

Figure 6 is a vertical section taken on line 6—6 of Figure 5.

Figure 7 is a horizontal section taken on line 7—7 of Figure 5.

The preferred structural embodiment of the invention is illustrated in connection with double doors ordinarily employed in railway house cars, adapted for shipment of bulky lading. The invention, however, is not restricted to such doors but may be used in railway cars embodying single door constructions. As illustrated, the door 10 constitutes the main door and the door 11 the auxiliary door. Each of these doors is preferably provided with a plurality of horizontal corrugations such as indicated at 12 and 13, respectively. The auxiliary door 11 additionally is provided with a metallic jamb or post 14, adapted to receive a wooden nailing strip 15. The post 14 is secured

to the front edge of the door 11 by means of rivets 16 which function, additionally, to fasten between the door and the post a Z-bar stop member 17, against which the main door is adapted to abut in the closed position of said doors. A knee brace 18 secured adjacent its ends to the post and to the auxiliary door serves to prevent rotation of the post under impact.

The operating device of the instant invention embodies an actuating lever 20 comprising the arms 21 and 22 which in the embodiment illustrated are angularly related to each other. The arm 21 of the operating lever is formed adjacent its end so as to provide a handle 23 by which said lever may be actuated. The operating lever 20 is pivotally supported preferably upon the main door 10 for movement about two axes substantially at right angles to each other. For this purpose the main door 10 has secured thereto by means of rivets 24 a fastener 25. This fastener may advantageously be positioned upon a horizontal corrugation 12 of the main door and be secured thereto by the rivets 24 extending through the fastener, the horizontal corrugation and a backing plate 26 lying on the inside of the corrugation. An integral boss 27 extends outwardly from said fastener and is adapted to pass through an eye 28 formed in the end of the operating lever 20. A washer 29 is positioned over the end of the boss and a rivet 30 is utilized to secure said washer, as well as the fastener and backing plate, to the door. The washer 29 prevents the operating lever from being displaced from the boss. Projecting outwardly from the fastener 25 is an abutment member 31 positioned preferably between the boss and the adjacent end of the main door. Extending inwardly from said fastener is a projection 32 adapted to extend through aligned openings in said door and in a reinforcing member 33 positioned in the vertical corrugation 34. It is observed that the eye portion of the operating lever through which the boss extends lies at an angle to said boss in the position of the operating lever shown in Figures 1 and 3 of the drawings. By this construction it is clear that the operating lever may not only swing about said boss in a vertical plane but may be moved outwardly in a substantially horizontal plane for a purpose which will hereinafter appear.

The arm 21 of the operating lever has its inner face recessed as indicated at 35, said recess providing an abutment 36 adapted to cooperate with the abutment 31 formed on the fastener as hereinafter set forth. Additionally, the arm 21

is provided with a slot 37, one end of said slot being extended in order to provide an abutment 38.

Adapted to coact with said operating lever is an arm pivotally secured so as to swing in a substantially vertical plane upon the auxiliary door 11 or other relatively stationary member. As illustrated the arm 40 is preferably mounted upon a boss 41 extending inwardly from an upstanding flange 42 formed preferably as an integral portion of a lock member 43. The lock member is secured as by rivets 44 to the crest of a horizontal corrugation 13 formed in the auxiliary door 11. The lock member is provided with a plurality of spaced outwardly extending housings 45 and 46. Intermediate these housings the lock member may be formed with a lug 47. The opening provided in the housing 45 is formed with one straight wall 48 and one inclined wall 49 and the opening in the housing 46 is similarly formed with a straight wall 50 and an inclined wall 51. The housings, consequently, are adapted to receive and properly retain a vertically reciprocating tapered locking pin 52. The arm 40 adjacent its free end is provided with a socket 53 in which the end of the arm 22 of the operating lever 20 is adapted to be received. It is apparent that the socket 53 provides abutments 54 and 55 adapted for optional engagement with the arm 22 of the operating lever.

When the door 10 is in its closed position as illustrated in Figure 1 of the drawings, and it is desired to impart initial movement to said door in the opening direction thereof, the locking pin 52 will be elevated so as to free the arm 21 of the operating lever. The handle 23 is then grasped and pulled outwardly so as to clear the housing members 45 and 46. This outward movement of the operating lever may be accomplished because of the angular relationship between the eye on said lever and the boss on the fastener. When the lever has been moved outwardly it may then be pulled toward the right as viewed in Figure 1, whereupon the end of the arm 22 will engage the abutment portion 55 of the arm 40. With the abutment portion 55 serving as a fulcrum the pull upon the handle 23 will be transmitted to the boss 27 formed on the fastener 25 and the door will be forced toward the right. The door 10 may then be opened to the extent desired. In the final closing movement of the door after it has been moved to substantially the position indicated in Figure 2 of the drawings, the arm 40 and the operating lever 20 will be in the positions shown in dot and dash lines in said figure. The arm 40 will then be swung to the full line position and the arm 22 of the operating lever will be engaged within the socket of said arm 40. By grasping the handle 23 on the operating lever the latter is then swung from its substantially vertical position to the horizontal position. During this swinging movement of the lever the arm 22 will engage the abutment portion 54 of the arm 40 and the door will be drawn into tightly closed position.

In addition to the operation of the operating lever 20 in the opening and closing movements of the door, said lever serves to lock the door 10 to the auxiliary door 11 or other stationary member. When the lever has been actuated to move the main door 10 to closed position said lever has assumed a substantially horizontal position. Said lever may then be moved in a substantially horizontal plane to position it between the housing members 45 and 46 formed on the lock member 43. In this positioning of the operating lever the lug 47 formed on the lock member will pro-

ject into the slot 37 provided in the lever. In addition thereto the abutment members 31 and 36 formed respectively on the fastener 25 and the operating lever will come into substantial engagement. The locking pin 52 may then be inserted through the housings and the locking operation completed by the insertion of a seal extending through aligned openings 55 and 56 formed adjacent the lower end of the pin 52 and the lower end of the lock member 43, respectively. In the projected or home position of the locking pin the straight side of said pin will abut the projection 38 formed adjacent the slot 37 on the operating lever.

It is observed that in the locked position of the operating lever engagement between the abutments 31 and 36 is obtained and that the clearance between the boss 27 and the eye 28 at the left of said boss is less than the clearance between the boss 27 and the eye 28 at the right of said boss. This relationship of the abutments, the boss and the eye on the operating lever is significant when the action of the lever as a lock is considered. It is apparent that in locked position the locking pin 52 will seldom, because of inaccuracies of construction, completely fill the openings in the housings 45 and 46. Consequently, the position of the locking pin will be determined by the position of the projection 38 formed on the operating lever. If the door has not been fully closed and, due to movement of the car over a track and the jarring of the door incident to said movement the door is further forced toward closed position, the boss will engage the eye on the operating lever so as to move said lever in the same direction as the door. The tapered pin will then be released from its engagement between the projection 38 on the lever and the inclined sides of the housing members and it will, consequently, through the action of gravity, move downwardly to absorb the clearance created by the movement of the hasp. Any tendency of the door in its locked position to move toward open position will, however, not be resisted by the eye on the operating lever and the boss formed on the fastener. Such movement will, however, be resisted by the substantially large bearing areas of the engaging abutments 31 and 36 provided, respectively, on the fastener and on the operating lever.

It is apparent that numerous changes and modifications of the structural embodiment of the invention will be apparent to those skilled in the art. It is intended that all such changes and modifications be comprehended within this invention and that it be limited only by the scope of the claims appended hereto.

I claim:

1. In combination with a relatively stationary member and a sliding door member, an arm permanently pivotally secured to one of said members, an operating lever permanently pivotally secured to the other of said members, said arm being provided with a recess forming a plurality of spaced abutments, the free end of said lever being seated in said recess and optionally engageable with said abutments.

2. In combination with a relatively stationary member and a sliding door member, an arm permanently pivotally secured to one of said members for swinging movement in a substantially vertical plane, an operating lever permanently pivotally secured intermediate its ends to the other of said members to provide a free end and

an operating end, and a socket formed in the swinging end of said arm, the free end of said lever being insertable into said socket for the purpose set forth.

5 3. In an operating device for a sliding door having a relatively stationary member associated therewith, an arm pivotally secured to said member for swinging movement in a vertical plane and an operating lever pivoted to said door, said 10 arm and said lever having free ends adapted for engagement to impart both initial opening and final closing movements to said door, the free end of said arm being formed with a socket in which the free end of said lever is adapted to be received, the free ends of said arm and lever being releasable while said arm is pivoted to said member, said lever being adapted to be secured 15 to said relatively stationary member to fasten

said door in closed position independently of said arm.

4. In combination with a relatively stationary member and a sliding door member, an arm pivotally secured to one of said members for swinging movement in a vertical plane, an operating lever pivotally secured intermediate its ends to the other of said members, said arm and lever having free ends adapted for engagement to effect initial opening and final closing movements 10 of said door member, the free end of said arm being formed with a socket in which the free end of said lever is adapted to be received, the free ends of said arm and lever being releasable while said arm is pivoted to said member, and locking 15 means for detachably fastening said lever to said first mentioned member.

WILFRED A. BEAUCHAMP.
